UNITED STATES PATENT OFFICE.

ABRAM K. BAER, OF BALTIMORE, MARYLAND, ASSIGNOR TO STROUSE-BAER COMPANY, OF BALTIMORE, MARYLAND, A CORPORATION OF MARYLAND.

ADJUSTABLE GARMENT.

Application filed November 19, 1921. Serial No. 516,360.

To all whom it may concern:

Be it known that I, ABRAM K. BAER, a resident of Baltimore, in the county of Baltimore and State of Maryland, have invented 5 certain new and useful Improvements in Adjustable Garments, of which the following is a specification.

My invention relates to garments, and more particularly to a garment, the body lines 10 of which are primarily straight but which may be changed to a garment having a tight waist-band.

While my invention is equally applicable to garments such as shirts, blouses or waists, 15 I have herein shown the same as employed in connection with a middy blouse.

Particularizing, my invention consists essentially in so arranging the bottom of the garment that it may be adjusted to assume 20 various lengths and may furthermore in one of its adjusted positions be fixed to simulate a waist-band, the size of which will be sufficiently shortened to fit tightly around the waist of the wearer.

25 Another feature of importance of my improved garment arrangement, and one that lends materially to the attractiveness of the same, is that the lower portion of the garment in its shortest adjusted position satisfactorily resembles a waist-band, the fastening means being entirely hidden from view. This effect is enhanced by the fact that the length of the simulated waist-band is shortened and fits snugly about the wearer's waist.

30 The various features and advantages of my invention together with the details of construction will be more fully amplified in the accompanying specification and drawing in which:

40 Fig. 1 is a perspective view of a middy blouse constructed in accordance with my invention in its shortest adjusted position,

Fig. 2 is a similar view with the middy blouse placed in its intermediate adjusted position,

Fig. 3 is a similar view with the middy blouse shown in its other extreme position, and

Fig. 4 is a fragmentary perspective view 50 showing more in detail the securing means for the lower edge of the middy blouse.

As stated hereinbefore, my invention may be used with equal effectiveness upon various 55 forms of garments such as shirts, blouses,

waists or the like but in the drawings I have illustrated the same as used in connection with a middy blouse 10, the body portion 11 of which is designed so that its lines are as usual, straight, the bottom portion 12 thereof being practically of the same diameter as the body 11.

It is in connection with the lower portion of the garment that my improved invention is employed and to this end at each 60 side thereof and to what is normally the inside of the garment, I secure two pair of fasteners 13, spaced apart a suitable distance for a purpose to be more fully hereinafter described. While these fasteners may be of 65 any desired type, I have here shown them as snap fasteners.

In Fig. 3 the garment is shown as being worn with the bottom portion 12 thereof unfolded or in other words in the same 70 manner in which middy blouses are generally worn.

In Fig. 2 the garment is shown with the bottom portion 12 folded upwardly upon the body 11, the fold occurring along the line 80 indicated at 14 in Fig. 3 and which may furthermore, be the line of stitching for the hem of the lower edge of the garment. Obviously, the length of the garment is shortened, the straight line effect thereof being 85 however, unaltered.

In Fig. 1 the garment is shown with the waistline thereof contracted so as to fit snugly around the waist of the wearer and this is accomplished in the following manner: By folding the lower portion 12 of the garment the fasteners 13 which were previously on the inside are exposed and brought into operative position where they may be utilized. The folded portion of the garment 90 is gathered at the sides to which the fasteners 13 are attached so as to reduce the diameter thereof and take up the slack in the garment, and held in this gathered position by the fasteners 13. This is clearly ill-

95 lustrated in Fig. 4 and here it will be seen that the lower portion 12 which has been previously folded upon the body 11 is gathered so as to bring the two halves of the fasteners 13 together, thus forming a 100 loop or plait 15 at each side of the garment. This reduction in the waist-line of the garment is sufficient to cause it to snugly fit the 105 waist of the wearer. This gathering of the garment at the waist-line thereof tapers off 110

into the body which is now of somewhat a greater diameter than that of the waist-line. The plait or loop 15 formed at each side of the garment at the folded portion is not 5 visible because it is covered by the fold 12 as clearly illustrated in Fig. 1. The folded portion 12 of the garment which now fits snugly around the waist of the wearer simulates a belt and the appearance of the garment has been changed from that of the 10 straight-lined garment without a waist-line to a garment of shorter length with a tight fitting waist-line.

By folding the portion 12 back upon the 15 body portion 11 of the garment, the garment is not only shortened in length but the portion thereof which is made to resemble a waist-band or belt, is made more substantial by the several thicknesses of material. The 20 garment in its shortest position of adjustment therefore, is not only comfortable but presents a neat and attractive appearance.

In view of the propensity of my invention for use in connection with garments of various types hereinbefore mentioned, I do not 25 wish to be limited to the specific embodiment herein illustrated, but reserve the right to

make such changes in the form thereof as may come within the purview of the accompanying claims.

Having thus described my invention, what I claim is:

1. In an adjustable middy blouse, a body having a bottom portion adapted to be folded to shorten the garment, said folded portion being adapted to be folded vertically at the sides of the garment to shorten the garment circumferentially and pairs of snap fasteners arranged at the lines of vertical folds for retaining the same in folded position. 30

2. A middy blouse having a bottom portion adapted to be folded to shorten the garment, said folded portion being adapted to be folded vertically at the sides of the garment to shorten the same circumferentially, pairs of spaced snap fasteners secured to the bottom of the garment on the inside and exposed when said bottom portion is first folded, said fasteners being arranged along the 45 lines of vertical folds, the engagement of said fasteners retaining the vertical folds in position. 50

ABRAM K. BAER.
